UNITED STATES PATENT OFFICE.

ALBERT T. VAN ALSTYN, OF NEW YORK, N. Y.

CLIP-TAG FOR PRICE-MARKING SILK GOODS.

1,190,821.

Specification of Letters Patent.

Patented July 11, 1916.

Application filed August 29, 1912. Serial No. 717,673.

To all whom it may concern:

Be it known that I, ALBERT T. VAN ALSTYN, a citizen of the United States, residing in New York city, in the county of New York and State of New York, have invented certain new and useful Improvements in Clip-Tags for Price-Marking Silk Goods, of which the following is a specification.

This invention relates to that class of labels or tags usually affixed or affixable to fabrics, and to dry-goods generally, by means of some kind of metallic clip, and commonly known as price-tags.

A principal object of my present improvements is to furnish a combined tag and clip,—that is; a clip-tag,—adapted to be safely applied to delicate and expensive fabrics, and which may also be readily removed from such fabrics without injury either to the clip or to the fabric, so that by means of re-marking or using small renewable price labels, the clip-tag may be employed in succession for marking a considerable number of articles.

For accomplishing those purposes, a further object, among others, is to furnish a clip in which the fabric-holding hooks will be located on spring arms arranged and connected with other parts of the clip in such a manner as to distribute the draft upon the hook arms to a plurality of bearing faces for each of said arms; also, to provide a construction for the clip whereby a clear space will be provided for the reception of the edge or selvage of a fabric and thereby avoid injury due to the accidental drawing or wedging of the edges of such fabrics in between portions of the wire from which the clip may be made or between normally contiguous portions of the wire and the card; also, to provide an arrangement in which the hook-arms have a working fulcrum consisting of a portion of the transverse head-bar of the clip, this head-bar being located crosswise to the pair of hook-arms and between these arms and the card.

Another object of the invention is to make the points of the clip needle-pointed and well sharpened to prevent the breaking of the threads in fine mesh delicate woven fabrics.

In the drawing accompanying and forming a part of this specification, Figure 1 is a plan view of a clip-tag made in accordance with my present invention. Fig. 2 is a side elevation of the clip-tag as seen from below in Fig. 1. Fig. 3 is an end elevation of the

tag and clip as seen from the right hand in Figs. 1 and 2. Fig. 4 is a perspective view of a modification on a larger scale, illustrating the organization of members, into which the metal part of such modification is formed in the completed clip. Fig. 5 is an enlarged side elevation of the clip, corresponding in position to Fig. 2, and showing the card or tag broken away. Fig. 6 is a view taken on the line Y—Y, Figs. 1 and 5; this view showing the parts at the right-hand of the line Y—Y as seen from the point at the left-hand thereof. Fig. 7 is a cross-sectional view on the line X—X, of Fig. 4, showing the parts at the right-hand of said line as seen at the left-hand thereof, this view showing the upward extensions forming additional stop faces, and being a modification of the embodiment shown in Fig. 6.

Similar characters designate like parts in all the views. Duplicate parts, however, are generally distinguished by the addition of a prime mark, since the complete clip comprises two similar halves or side portions, which, as to their relative formation, are right-handed and left-handed, respectively. Thus the hook-arm on one side is designated by *e*, and on the other side by *e'*, although in themselves these arms are or may be exactly alike, and in referring to either one alone, they are sometimes hereinafter designated simply as the hook-arm *e*; and similarly as to other duplicate details, on whichever side of the clip such details may in fact be located.

While the clip, as illustrated in Figs. 1, 2 and 3, is shown applied to a relatively small tag or card, as *k*, and while the clip itself is shown of a relatively large size for convenience of illustration, it will be understood that my present invention is particularly applicable to clips of relatively small dimensions and for use on cards of varying sizes and thicknesses.

With the clip-tags heretofore commonly employed, a considerable loss frequently occurs through the breaking of a thread or threads in fine-mesh delicate woven fabrics, particularly with the clip as applied to silks of the finer grades, and I have discovered that it is particularly desirable, in order to avoid such injuries to those kinds of valuable goods, to make the hook points, as *o o'*, needle-pointed and well sharpened and also to make the clip itself of a relatively smaller wire than ordinarily employed. But when

the smaller wire is used, the card or tag has a reduced power of resisting the strains or draft to which these articles are frequently subjected, and in order to provide for these 5 conditions, and meet emergencies and accidents, I have provided an organization of the several members of the clip whereby each of the hook-arms, as e and e' , will be directly connected with other parts of the 10 clip which are so arranged as to each have a bearing at two locations against the card, and to bear at both points in the same direction, and in a direction for directly resisting the draft upon the hook, as hereinafter more 15 fully described.

The hook-arms e e' are to some extent spring-arms, and since their hooks, o o' , respectively, are directed or bent downwardly (toward the card), and preferably rearwardly, (see Figs. 2, 4, 5, and 7) the points 20 of said hooks bear upon the card k , which thus protects the hooks and leaves the upper bends, at 6 6', of a form adapted for preventing them from catching onto and 25 thus injuring goods to which the clip is not attached. The direction of the draft or pull upon the hooks o o' and their arms e e' , respectively, is indicated by the arrow r .

The hook-arm e is shown integrally connected by the bend, at 4, with the short and nearly vertical part or member d which takes its bearing against the abutment or bearing face n of the card; and through the part d the hook arm e is further connected 30 through the turn at 3 with the lower parallel member c which extends forwardly from the edge bearing n , and at the bend 2 turns upwardly as indicated at b , for thereby delivering a part of the total draft-force 35 against the abutment at t . In this way when the fabric is subjected to strain relatively to the card or tag k , this strain is transmitted through the said parts e , d , c , and b , (see Fig. 5) and is delivered against 40 the card k at the two bearing points n and t , which are thus brought into direct co-action 45 for each one sustaining a part of the total load or draft. In this way any pull or draft upon the hook o , in the direction of the arrow r , is transmitted to two bearing points 50 (as n and t), which lie in substantially the same vertical plane as the hook arm e , so that the strain is received on the card in a 55 direct manner and in a way best adapted for sustaining a relatively high degree of strain with a minimum tendency to distortion or injury of either the clip or the card.

As regards the total strain or draft upon the card, when the hooks 6, 6' are pulled in the direction of the arrow r , Figs. 5 and 6, both of said bearings, as at t and n , may be said to be draft-bearings, but as regards the force so applied to the bearing t , whether this force be transmitted through the member c or the member a , or through both of

these, the action may be said to be a thrust; and relatively to these members a and c , the bearing t may therefore be considered as a thrust bearing.

From the upper ends of the members b b' , 70 the clip-structure continues through the bends at 1—1', and the side-bars a a' , and at the bends 5—5' joins by an integral connection with the extended ends of the head-bar h , thus completing the system of clip components. The said head member, h , lies upon the card adjacent to the outer bearing n , and thus mechanically coöperates with the hook arms e and e' ,—and as a fulcrum-bar therefor,—and with the lower parallel 75 members c and c' for securing the stability of the clip upon the card, and thus insures a more permanent adjustment and relationship of all of the parts in connection with the distribution of the total strain on each 80 hook arm as between the two bearing faces, as n and t , therefor. The primary draft-abutment, n , is preferably on the unbroken outer edge of the card, while the secondary and supplemental draft-abutment, t , is 85 located within the card, and is a thrust-resistant for the member c .

The head h of the clip is shown extended in length (see Figs. 1, 3, 4, 6 and 7) to a length considerably in excess of the direct 90 distance between the hook arms e , e' , and by this means spaces are provided at v — v (see Figs. 1, 4 and 7), so that when the fabric edge is fully drawn back, the fabric lies under the hook arms e and e' , extends outwardly and upwardly through the spaces 95 v — v , and then over the said side arms a a' where these turn forwardly at 5—5', from the laterally extended ends from the said head h . This peculiar arrangement of the 100 several members, provides for bringing the extreme rearward end of the hook arms e and e' closely down onto the head-bar h , (when the clip is completed in engagement 105 with the tag k), so that a clear space is provided under the said hook arms all of the 110 way from the hooks backwardly to the forward side of the said bearing h , whereby the fabric, as f f , Figs. 2 and 7, is permitted to be drawn fully back against the stop face at 115 s s' without being subjected to any frictional engagement or strain other than is required to draw the same under the hooks; this avoids a prolific source of injury and 120 loss which has heretofore been incurred by the use of various kinds of price tags.

When the fabric, as f , Fig. 2, is drawn back under the hook arms e and e' , until the edge of the fabric finally comes against the said combined head member and stop-face member h , the fabric then lies above the side members or head arms, a and a' , (see Fig. 7) and the edge of the fabric then crosses the bar h at the points s and s' ; thus 125 the forward side of the head h constitutes a 130

positively acting stop-face for preventing the edge of the fabric from being drawn backwardly into a wedging engagement between the rounded transverse surfaces of the 5 clip members h and e, e' .

In the construction just described, and as well shown in Fig. 5, the clip comprises a three-bend four-sided loop, consisting of the members a, b, c and d , and one end of which 10 connects with the hook-arm e , while the other end located above the card k , connects with the extended end of the head-bar. The upper said loop-member a , by integrally connecting at the bend 5 with the 15 head-bar h ,—this bend being located to one side of the connected hook-arm,—brings directly forward to the member b and abutment t , any forward draft which the arm e exerts upon the head h ; and the outer member d , by integrally connecting through the 20 bend at 4 with the rearward end of the arm e , thus hooks over and upon said head-bar, or stop-face member, to form a loop-lock whereby the rearward end of said loop is 25 securely held into firm engagement with the card k , and with the head-bar at the extreme rearward end (or edge) of said card, while each loop incloses a part or edge-portion of the card below said head-bar.

In the organization as herein described of the several structural features, an edge-portion of the card,—as, for instance, the portion between the members b and d , Figs. 5 and 6,—may be said to be inclosed in a 30 loop which consists of the members a and c in connection with the members b and d ; and such loop may also be said to be connected at one end thereof, as at 5, to the head-bar, or transverse stop-face member, 35 as h , while the other end thereof is connected with the hook-arm, as e , by a bend, as 3, d , 4, which constitutes a hook for holding the said stop-face member downwardly upon the card. Also, the said loop, 40 as regards some features, may be said to comprise four sides or members, as a, b, c, d and three bends, as 1, 2, 3; and this three-bend four-side loop may be said to connect with the hook-arm, as e , by a bend, as 4, 45 forming a hook-engagement with the said head-bar h , this being transversely connected with a side-member, as a , of said loop. In the completed clip-tag, the organization above described, is such as to provide 50 the two hook-resisting bearings, as t and n , located one remotely from the other, and located for each receiving a part of the strain or draft due to pulling on said hook, as 6 or 6'.

For the purpose, among others, of making the forward side of the head-bar h available and practically operative for a stop-face, the hook arms $e-e'$ are required to 55 pass over, upon and across said bar at points relatively remote from the bends, 5—5, at

which the head-bar connects with the side members a a , since otherwise the required free spaces at v v , would not be provided, and a liability would exist for a wedging action to take place of the goods between 70 adjacent or contiguous members of the clip. Thus the loop member a connects through the bend 5 at a point sufficiently distant laterally of the hook-arm e , to form a free and clear space between the loop-member and 75 the hook-arm. In Figs. 4 and 7, I have shown the preferred construction of the bar h when arranged as above described, the outward extensions 8, 8' of that bar being here shown curved upwardly for modifying 80 the form of the stop-face at s, s' , and also form stops for preventing the outward spreading of the arms e, e' .

The hooks o, o' , being protected by the card k , and the complete clip-tag having no upwardly or laterally-projecting points or prongs, therefore these tags may be freely handled in quantities in the hands without risk of injury to the operator by pricking through the skin, (not an infrequent occurrence), and without liability of damaging valuable silks and garments by blood stains due to such injuries. Owing to the described structural features, these clip-tags occupy a minimum of space in packing, and do not interlock or become tangled in the packages when being packed or unpacked, and may be handled by the operators with great facility and rapidity, thereby materially reducing the time and labor 95 required for applying the tags to the goods.

In practice, the hooks o, o' may be elevated before putting the fabric in place thereunder; this is readily done in the case of small clips, by using the finger-nail, but 105 in all cases a suitable card or blade, as indicated at p , Fig. 2, may be first slipped under the hooks. And when the fabric is in place, the hooks may be released by applying the blade p as in Fig. 2, and then pushing it under the hooks, when the fabric and blade may be withdrawn together.

Having thus described my invention, I claim:

1. In a clip-tag of the class specified, the 115 combination with a card and with a pair of hook-arms lying in a plane adjacent to the card face, and each having a hook at its free end, of a transversely-disposed combined head-bar and top-face member located on the card under the hook-arms and holding said arms at the ends thereof opposite to the hooks above the card face for thereby providing a selvage-space between the hook-arms and the card face adjacent to 120 said head-bar, and said head-bar forming a stop-face at such position for the edge of the fabric.

2. In a clip-tag of the class specified, the combination with a card and with a pair of 130

- hook-arms each having a hook facing the card, of a transversely-disposed combined head-bar and stop-face member located on the card under the hook-arms and holding 5 said arms at the ends thereof opposite to the hooks above the card face for thereby providing a selvage-space and a stop-face for the edge of a fabric; and a pair of integrally-connected three-bend, four-sided 10 loops each having one end thereof located above the card and each inclosing a part of the card below said head-bar, and said loops having the ends thereof above the card connected, respectively, to the opposite ends of 15 said transverse stop-face member by bends each located to the outside of one of the hook-arms, substantially as described.
3. In a clip-tag of the class specified, the combination with a card and with a hook-arm having a hook, facing the card, of a transversely disposed stop-face member located on and near the edge of the card and under the hook-arm, and holding said arm at the end thereof opposite to the hooks above 25 the card face for thereby providing a clear

selvage-space for a fabric, and a loop arranged to have a draft bearing at two points on the card and having one end connected to said transverse stop-face member, such connection being distant laterally of the 30 hook-arm sufficient to form a free space between such loop member and the hook-arm, and said stop-face member having an upwardly curved portion.

4. In a clip-tag of the class specified, the 35 combination with a card and with a pair of hook-arms each having a hook, facing the card, of a transversely disposed stop-face member located on and near the edge of the card and under the hook-arms, and holding 40 said arms at the ends thereof opposite to the hooks above the card face for thereby providing a clear selvage-space for a fabric, and having the stop-face member provided with upwardly curved portions at the outer 45 sides of the hook arms, respectively.

ALBERT T. VAN ALSTYN.
